UNITED STATES PATENT OFFICE.

JOHN J. GILBERT, OF PORT WASHINGTON, NEW YORK, ASSIGNOR TO WESTERN ELECTRIC COMPANY, INCORPORATED, OF NEW YORK, N. Y., A CORPORATION OF NEW YORK.

SUBMARINE SIGNALING.

Application filed June 1, 1926. Serial No. 112,840

This invention relates to submarine signaling and particularly to terminal sections for loaded submarine cables.

An object of the invention is to reduce the disturbing effect due to extraneous electric waves picked up by the cable.

I have hitherto proposed to decrease the interfering effect on received signals of extraneous electric waves picked up by a cable by providing an auxiliary loaded cable similar to the main cable and extending from the terminal apparatus to a location at sea about 500 ft. in depth. At the end of this auxiliary cable the core is connected to a metallic cap making contact with the sea water and near this sea-earth connection, a length of high resistance conductor is spliced into the core. This section of high resistance conductor is made equal in resistance to the characteristic impedance of the main loaded cable, which, when the cable is suitably loaded, is practically a pure resistance at the frequencies of importance in cable work. In the terminal arrangement at the New York end of the permalloy loaded cable recently laid between New York and the Azores, this type of sea-earth connection and terminating impedance are used.

In accordance with a preferred embodiment of the present invention a twin core cable section, the cores of which have electrical characteristics differing from that of the loaded core of the main cable, is joined to the main cable and a terminating impedance grounded at sea. This terminal cable section extends to such a depth at sea that the amplitude of electrical disturbances originating near the surface of the sea and reaching the cable is small as compared to the amplitude of the signal current at this point. The terminal section should also extend to a point at sea beyond which disturbances originating under the surface, such as that caused by nearby parallel cables, is negligible. It is preferable to employ terminal sections in which the two cores have similar electrical characteristics but some advantages may be derived even when employing a terminal section in which the cores have dissimilar electrical characteristics.

The invention may be more clearly understood by referring to the accompanying drawing in which Fig. 1 shows a twin core non-loaded terminal section connected to a

main cable and a terminating impedance at one end and to cable terminal apparatus at the other, and Fig. 2 shows a portion of a twin core terminal section in which the degree of loading is diminished progressively from the main cable to the terminal apparatus.

In the drawing the main cable 20 comprises the conducting core 5, a wrapping of loading material 6 and an insulating material 7, such as gutta percha, in which the loaded conducting core is embedded. The loading material 6 may be of any material having suitable magnetic properties as, for instance, a nickel-iron alloy containing 78½% nickel and 21½% iron, which is produced in accordance with the process described in patent to G. W. Elmen, 1,586,887, issued June 1, 1926. This alloy has the advantage of having a permeability 20 or 30 times that of iron at magnetizing forces of the order of 0.01 to 0.10 gauss and it has been found that the characteristic impedance of a cable loaded with such a material has a negligible reactance component at frequencies of interest in connection with submarine cable signaling systems. The metallic protecting sheath 22 is positioned about the insulating material 7 and a material 21, pervious to water, is wrapped about the sheath 22.

The terminal cable section comprises the twin core conductors 9 and 10 surrounded by the insulating material 8, these conductors having electrical characteristics different from the electrical characteristics of the main cable. The conductors 9 and 10 as shown in Fig. 1 are non-loaded but these conductors may, in another aspect of this invention, be loaded in a different degree from that of the main cable. For instance, the loading may be tapered so that the degree of loading is progressively diminished from the main cable to the receiving apparatus. In this case, the electrical constants of corresponding small sections of the two conductors are preferably equal. In Fig. 2 is shown a portion of a twin core terminal section in which the conductors 27 and 28 are loaded to a different degree at different portions of the cable respectively, by means of the loading material 29 and 30. Referring again to Fig. 1, one end of the conductor 9 is connected to the core 5 of loaded cable 20 and the other end is connected to the terminal apparatus. Conductor 10 connects, at one end, to the terminal ap-

paratus and is grounded at the other end to the metallic protecting sheath 12. The protecting sheath 12 and the pervious material 13 are similar to and preferably continuous with the sheath 22 and the pervious material 21 respectively of the loaded cable 20. The terminating impedance 14 is spliced into conductor 10 near its grounded end. As stated above, the characteristic impedance of a loaded cable is nearly a pure resistance, the value of which may be calculated from the inductance L and the capacity C of the cable by the formula $R = \sqrt{L/C}$. A preferred form of terminating impedance consists of a suitable length of high resistance stranded wire, such as nichrome, having a total resistance substantially equal to the characteristic impedance of the loaded cable, that is, the portion of the cable seaward from the sea-
earth connection. This artificial line is preferably spliced into the cable conductor by soldering the individual strands of resistance wire to one or more strands of the cable conductor.

25 The terminal apparatus is of the usual type used in cable systems employing duplex operation and consists essentially of the transmitting apparatus 15, receiving apparatus 16, the condensers 17 and 18 of equal capacity and the grounded networks 25 and 26 which are employed to correct for unbalances between the signaling conductor and the sea-earth conductor. A system employing such networks is described in detail in U. S. patent to O. E. Buckley, No. 1,567,316, December 29, 1925.

We have then a terminal section for a loaded cable in which the conductors 9 and 10 are connected, at one end, to the receiving apparatus 16. At the other end, conductor 9 is connected to the loaded cable 20 and conductor 10 to the grounded terminating impedance 14. This terminal section extends from the terminal apparatus to a location at which the sea is substantially 500 ft. deep. At such a depth the electrical disturbances originating at the surface of the sea cause a negligible disturbing current to flow in the cable. The terminal section should, furthermore, extend to a location which is at a considerable distance from submarine disturbances as, for example, other cables, so that the effect of these disturbances will be reduced to a negligible value. Electrical disturbances picked up at any point along the terminal section will cause equal voltages to be induced in each of the conducting cores 9 and 10. Where the cores are similar throughout and their terminating impedances, i. e., the impedances of the loaded main cable and the artificial line, are equal, the magnitude of the disturbing currents in each core will be equal at any position on the terminal cable section. Under these conditions, the disturbing currents reaching the receiving apparatus

will be equal in magnitude but opposite in phase and will therefore annul each other.

While the impedance of the terminating impedance is preferably made equal to the impedance of the cable seaward from the sea-earth connection and while the cores of the terminal section are preferably similar electrically, yet, where these conditions are not found, disturbing currents due to reflected waves may be prevented by maintaining a correct relation between the impedance values of these elements. This relation should be such that the ratio of the characteristic impedance of the conductor 9 to that of conductor 10 is equal to the ratio of the characteristic impedance of the main cable 20 to that of the terminating impedance 14, that is, where Z_9 , Z_{10} , Z_5 , and Z_{14} , represent respectively, the characteristic impedances of the conductors 9 and 10, the cable 5 and the terminating impedance 14,

$$\frac{Z_9}{Z_{10}} = \frac{Z_5}{Z_{14}}$$

The improved terminal cable section for loaded cables has been shown and described in connection with one form of duplex terminal apparatus. It is adapted, however, for simplex as well as duplex systems and for other terminal arrangements of duplex apparatus than that shown. For example, the invention may be employed in such systems as those disclosed in U. S. patent of H. S. Osborne, No. 1,390,580, September 13, 1921. It has an additional advantage when used in duplex systems over simplex systems, in that the difficult problem of providing a balancing network for balancing the head end of the cable for duplex operation is simplified.

105 What is claimed is:

1. In a submarine signaling system, a loaded cable, receiving apparatus and a sea-earth connection for said cable, and a twin core terminal section connecting said cable to said sea-earth connection through said receiving apparatus, said terminal section having a distributed inductance different from said cable.

2. In a submarine signaling system, a loaded cable, receiving apparatus and a sea-earth connection for said cable, said sea-earth connection being located at a sea depth of substantially 500 feet, and a non-loaded twin core terminal section connecting said loaded cable to said sea-earth connection through said receiving apparatus.

3. In a submarine signaling system, a loaded cable, terminal apparatus therefor, a terminating impedance, a non-loaded twin core terminal section connecting said terminal apparatus with said loaded cable and said terminating impedance, and a sea-earth connection for terminating said terminating impedance.

4. In a submarine signaling system, a load-

- ed cable, terminal apparatus therefor, a terminating impedance, a non-loaded twin core terminal section connecting said terminal apparatus with said loaded cable and said terminating impedance, and a sea-earth connection, located at the seaward end of said terminating impedance and at a sea depth of substantially 500 feet, for terminating said terminating impedance.
- 5 5. In a submarine signaling system, a loaded cable, a terminating impedance for simulating the impedance of said cable and located at sea at such a depth that the cable located farther out at sea will be substantially free 10 from the influence of external disturbances, a receiving circuit for receiving messages transmitted over said cable, and two similar conductors connected to said receiving circuit, one extending to said terminating impedance 15 and the other to said cable at a point corresponding in location to that of said terminating impedance, said similar conductors having impedance characteristics different from said loaded cable.
- 20 6. In a submarine signaling system, a cable, a two conductor terminal section therefor, the conductors in which have impedance characteristics different from said cable, a terminating impedance, the two conductors of 25 said terminal section being connected to said

cable and to said terminating impedance respectively, and the ratio of the impedance of said cable to that of said terminating impedance being substantially equal to the ratio of the impedance of the terminal conductor 35 connecting to the cable to the impedance of the terminal conductor connecting to said terminating impedance.

7. The method of diminishing the interfering effect of extraneous electric waves picked up by a loaded submarine cable employing a non-loaded twin core terminal section and a sea-earth connection, which comprises immersing said sea-earth connection in a depth of water of substantially 500 feet and extending said twin core terminal section to said sea-earth connection.

8. In a submarine signaling system, a loaded cable, receiving apparatus and a sea-earth connection for said cable, and a twin core 50 terminal section connecting said loaded cable to said sea-earth connection through the receiving apparatus, the electrical characteristics of said twin cores being different from the electrical characteristics of said loaded 55 cable.

In witness whereof, I hereunto subscribe my name this 28th day of May A. D., 1926.

JOHN J. GILBERT.
